(57) **CLAIM**

The ornamental design for a casing for binoculars, as shown.

DESCRIPTION

FIG. 1 is a perspective view of the top front and left side of a casing for binoculars showing my design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a rear elevational view thereof.

The elements shown in phantom lines do not constitute part of the claimed invention.

1 Claim, 3 Drawing Sheets
